SUCTION-PRESSURE-REGULATING
VALVE

Ferdinand F. Heiser, Wauwatosa, Wis., assignor
to Automatic Products Company, Milwaukee,
Wis., a corporation of Wisconsin

Application July 22, 1940, Serial No. 346,725

1 Claim. (Cl. 137—153)

This invention relates to an improvement in suction pressure-regulating valves for use with refrigerating systems.

An object of this invention is to provide a valve of this character which is effective to maintain the evaporator pressure at a desired level regardless of changes in load or variations in the suction pressure on the outlet side of the valve. The evaporator temperature may be maintained within very close limits.

One of the advantages of the valve is that it provides a means which makes it practical to operate two or more evaporators at different temperatures with a single condensing unit. This is usually necessary in multiple installations. While thermostatic expansion valves may be used for this purpose when the temperature differences are not too great, nevertheless when the temperature difference is over five or six degrees Fahrenheit, then the use of a suction pressure-regulating valve of the character disclosed in this application is most desirable and advantageous.

Another object of the invention is to provide a valve of this character having these advantages, and which is simple, compact, and closely organized in its construction, reliable and efficient in operation, advantageously adapted for use on systems of flooded, semi-flooded, or dry expansion types, and also adapted to be manufactured with economy from materials and by means of facilities ordinarily available.

Another object of the invention is to provide a valve of this character which may be set to maintain any one of a number of evaporator pressures over a wide range.

Other objects and advantages reside in certain novel features of the construction, arrangement, and combination of parts, which will be herein-after more fully described and particularly pointed out in the appended claim, reference being had to the accompanying drawing forming a part of this specification, and in which:

Figure 1 is a view in central, vertical, longitudinal cross section, showing a suction pressure-regulating valve involving the present invention; and

Figure 2 is a diagrammatic view of the control knob of the valve and illustrating the dial or scale which facilitates accurate adjustment of the valve to select the desired pressure setting.

Referring to the drawing, the numeral 5 designates the body of the valve. Integral with the body of the valve is an inlet fitting 6 which is externally threaded to adapt it to be connected up

to the tail or outlet end of the evaporator coil. Internally the valve is provided with a valve chamber 7 with which the inlet 6 is in open communication. An outlet fitting 8 is threaded into the lower open end of this chamber 7, as indicated at 9. A washer 10 between the flange of the fitting and the valve body hermetically seals the connection between these parts. The outlet fitting 8 is also externally threaded to adapt it to be connected to the suction side of the compressor.

The upper end of the outlet fitting is provided with two counterbores 11 and 12, the counterbore 11 being adapted to have a valve seat 13 fitted therein and secured thereto, and the counterbore 12 accommodating the head 14 of the valve proper, designated generally at 15. The head 14 of the valve is provided with a facing 16 which may take the form of a flat annulus of fibrous material, molded composition material, rubber, leather, or the like. This facing is held in position by a stud 17 which has its shank secured to the valve and its head overlapping the inner periphery of the facing, and also by means of a retaining ring 18 suitably secured to the periphery of the head of the valve and having an inwardly directed flange 19 overlapping the outer periphery of the facing. The exposed portion of the facing coats with the valve seat to control the flow through the valve.

The valve 15 has a valve stem 20 integral with its head 14, and slidably fitted in a tubular valve guide 21. The lower end of the valve guide 21 is enlarged and flanged as at 22, and the enlarged portion thereof has a circumferential series of openings 23 to provide for communication between the valve chamber 7 and the counterbore or space 12 which accommodates the head of the valve. The under side of the flange 40 of the enlarged end 22 of the valve guide 21 is engaged between the upper end of the outlet fitting 8 and the lower ring 24 of a strainer, designated generally at 25. The upper ring 26 of the strainer engages an inwardly directed shoulder 45 21 integrally formed with the valve body at the upper end of the valve chamber 7. The reticulated body portion of the strainer is suitably connected to the rings 24 and 26.

A coil spring 30 encircles the valve guide 21 and has its lower end abutting the enlarged portion 22 thereof and its upper end abutting a flanged washer 31 secured by a nut 32 and lock washer 33 to the upper end of the valve stem. The spring 30 is under compression and tends to bias the valve 15 to open position and causes the

upper end of its stem to bear against and follow the lower section or member 34 of a pressure pad, designated generally at 35, and suitably fixed to the central portion of a diaphragm 37.

The periphery of the diaphragm 37 is clamped between the upwardly inclined peripheral portion of a flange 38 integral with the upper end of the valve body 5, and a downwardly and inwardly directed peripheral portion 39 of a diaphragm or casing member 40. The portion 39 of the diaphragm casing member 40 is spun or rolled into secure mechanical engagement and hermetic sealing relationship with the periphery of the flange 38. The body of the casing 40 is provided with a vertical cylindrical or tubular extension 41 which is internally threaded.

An adjusting knob, designated generally at 42, is provided and includes a cap 43. An externally threaded sleeve 44 is combined with the cap 43 and has its lower end open and its upper end closed. The upper closed end of the sleeve 44 fits against the under side of the top of the cap and is rigidly interconnected therewith by virtue of provision of dowel pins 45 which may be formed integrally with the under side of the cap and which will project into the openings provided therefor in the upper end of the sleeve 44. Centrally, the upper closed end of the sleeve is formed with an internally threaded bushing 46. A screw 47 has its head engaged with the top of the cap and has its threads interengaged with the bushing 46. The external threads of the sleeve 44 are interthreaded with the internal threads of the extension 41 of the diaphragm casing. A spring 48 is interposed between the upper member of the diaphragm pressure pad 35 and the under side of the closed upper end of the sleeve. By turning the knob the compression of the spring 48 may be varied. In order to facilitate adjustment of the spring 48, and consequently to determine the pressure which the valve will maintain in the evaporator, the extension 41 of the diaphragm casing is provided with a series of graduations and numerals, designated at 50 in Figure 2. These graduations and numerals provide a pressure index or scale. Cooperable with this scale is a collar 51 which is carried by the sleeve 44 and has a lower edge 52 cooperable with the graduations and with the members of the pressure index or scale. Preferably the collar 51 is threadedly interconnected with the sleeve 44, and after it has been properly adjusted at the factory it is soldered in position as indicated at 55.

The valve is also provided with a gauge connection which is constituted of an internally threaded passage 60 communicating with passages 61 and 62 which lead to the valve chamber 7. A plug 63' is provided for the passage 60, and when this plug is removed the gauge (not shown) may be put in place. At the juncture of the passages 61 and 62 a valve seat 63 is formed. A needle valve 64 is cooperable with the valve seat, the needle valve being threadedly interconnected with the valve body, being provided with packing 65 and also with a cross slot 66 to facilitate its manipulation by a screw driver or the like. A cap 67 is provided for the outer end of

the opening which accommodates the needle valve, and after the gauge has served its purpose and is removed, the needle valve may be turned up to shut off communication between the passages 62 and 61, thereby precluding the possibility of leakage when the gauge has been removed.

The suction pressure-regulating valve above described maintains an even evaporator temperature by controlling the pressures in the evaporator. As the load increases in the evaporator, increasing the temperature and the evaporator pressure, the valve tends to open wider so as to maintain the predetermined pressure setting of the regulating valve. Then when the evaporator temperature begins to fall and the evaporator pressure tends to decrease, the valve begins to close again, thus maintaining the original pressure setting of the valve. The valve is of the throttling type tending to close off gradually as the evaporator pressure is reduced beyond a certain point. There is no sudden change to cause erratic operation of the balance of the system.

The scale 50, with which the lower edge 52 of the collar 51 coacts, is preferably graduated in pounds pressure, ranging from 10' vacuum to thirty pounds per square inch at which the valve operates. By turning the knob down until the edge 52 of its collar 51 coincides with the desired pressure setting, an immediate setting can be secured and it is not necessary to wait several hours before the system has settled down sufficiently to permit the valve to be adjusted to the proper pressure setting. After the knob adjustment described has been made, and the system has had a short time to settle down, the exact pressure setting can be secured by a gauge reading. The temporary setting will be accurate within a pound or so.

While I have shown and described one construction in which the invention may be advantageously embodied, it is to be understood that the construction shown has been selected merely for the purpose of illustration or example, and that various changes in the size, shape, and arrangement of the parts may be made without departing from the spirit of the invention or the scope of the subjoined claim.

I claim:

A pressure-regulating valve comprising a valve body having a chamber, an inlet to said chamber, said chamber having an opening to the exterior of said body, an outlet fitting inserted into said opening from the exterior thereof and connected thereto, two counterbores in said fitting, a valve seat carried in one of the counterbores in said fitting, a valve having a flat-faced head accommodated in the other of said counterbores and cooperable with said seat and having a stem, a tubular guide slidable on said stem and having a flange at one end, a spring encircling said guide and reacting between said flange and said stem, said valve, guide and spring being inserted as a unit into said chamber through said opening, said fitting being engaged with said flange to position said valve, guide and spring in said chamber, and a diaphragm cooperable with said stem to control the position of said valve.

FERDINAND F. HEISER.
